SPARK-PLUG.

1,284,151.

Specification of Letters Patent. Patented Nov. 5, 1918.

Application filed October 26, 1916. Serial No. 127,865.

To all whom it may concern:

Be it known that we, LEO A. SCHAUER and ERNEST C. MYERS, citizens of the United States of America, residing at Pittsburgh, in the county of Allegheny and State of Pennsylvania, have invented certain new and useful Improvements in Spark-Plugs, of which the following is a specification.

The present invention relates to improvements in spark plugs of the double-jump-spark type, and has the following objects and advantages in view in its construction. In this type the ignition spark within the engine cylinder is intensified by an auxiliary spark according to well established electrical principles thus getting full explosive value from the gas used. In our invention the auxiliary spark is formed within the plug itself thereby obviating the necessity of extra intensifiers sometimes used for the same purpose. The auxiliary spark gap is inclosed by a wire gauze which prevents same from igniting any surrounding explosive gases that may be in the vicinity of the plug in accordance with a well known principle, and yet is readily visible to the eye, thereby furnishing a means whereby the operator can ascertain whether the electric current is working properly within the engine. The small number of parts and the simplicity of their form and construction is an advantage, few parts being thereby provided that can get out of working order by vibration which is always present in some classes of engines.

With these and other objects in view to be explained hereinafter in this specification, we have illustrated in the accompanying drawings one complete embodiment of our invention constructed according to the best mode we have so far devised for the practical application of the principles of our invention.

Figure 1 is a central longitudinal section of our invention.

Fig. 2 is a view in side elevation of same.

Fig. 3 is a horizontal section taken on line 3-3 of Fig. 1.

Fig. 4 is a bottom plan view of Fig. 2.

The spark plug consists of the following parts. A cylindrical housing 1, having a terminal or electrode 2, a porcelain plug body 3, or other insulation which fits into the housing 1, the latter having annular shoulders 4 and 5. The shoulder 4 is protected by a yielding annular gasket 6, which

last rests on the complementary annular shoulder 7 of the housing 1. The housing 1 has the usual threads 8 for attachment to the explosive chamber of an engine. The porcelain 3 is secured in the housing 1 by a hollow coupling nut 9, with threads at 10 whereby it is attached to housing 1 as shown in the drawing. A gasket 11 is interposed between shoulder 5 of the porcelain 3 and the bottom surface of coupling nut 9. A central conductor 12, passes through the center of porcelain 3, and is provided with a flange 13 formed thereon which carries an annular packing ring 14. The latter 14, and flange 13 are adapted to fit into a cavity 15 formed in the base portion of the porcelain plug body 3. At its upper end conductor 12 has a threaded portion 16 which carries a nut 17, for the evident purpose of holding 12 securely in the porcelain 3.

The porcelain 3 has an aperture 18 which passes horizontally through the same, and conductor 12 projects above the nut 17 and into the aperture 18 for a purpose described below. A threaded conductor 19 is positioned in the upper end 20 of porcelain 3 and is secured by the nuts 21, 22, the latter being also used for adjustment purposes. A lock washer 23 is interposed between 22 and cap 24, the latter being positioned on the end of 3 as shown. The lower end of conductor 19 projects into the aperture 18 in similar fashion to the end of conductor 12, and into intimate relation therewith, and it is seen that the regulation of the distance between the electrodes at 33 is readily accomplished by nuts 21, and 22. A slot 25 is provided in the upper end of conductor 19 for turning the same through nuts 21, 22. The lead wire 38 is inserted in the opening 26 and is secured to the plug by nut 27.

The porcelain 3 has an annular shoulder 28 and a portion 29 of reduced diameter, and over which is fitted a cylindrical metallic wire gauze 30, which last is held in place by the downwardly projecting annular flange 31 of the cap 24. The bottom edge of the gauze 30 is reinforced by a metal strip 32 as shown. It is a well known electrical fact that if an auxiliary spark gap is introduced into a circuit that the ignition spark at any other point say 34 in the circuit will be intensified thereby. Hence it is at once seen that by introducing the auxiliary gap at 33 the spark at the ignition point 34 will be very much intensified, insuring a stronger

spark and positive explosion of gas in the cylinder of the engine. The ignition spark being intensified at 34 also has the effect of reducing the carbon deposit that ordinarily 5 collects on the points 2 and 35 of the spark gap electrodes. The auxiliary spark gap 33 having air constantly between the ends 36, 37 of the conductors is thereby provided with the necessary air resistance at this point, 10 which it will be understood, will intensify the spark at 34, as before mentioned.

The metallic wire gauze 30 is for the dual purpose of preventing the ignition of surrounding gases, in accordance with a well 15 known scientific principle, and also to enable the operator to observe the auxiliary spark gap in order that the adjustments can be made to suit varying conditions in the plug. And it also can be determined if the plug is 20 "firing" or not at the ignition gap, due to the electric current working or not working properly. The advantage of being able to determine instantly by mere inspection of the auxiliary spark gaps on a series of plugs 25 on the cylinders of an engine, is at once apparent, and provides an index as to the working of the electric current.

As an additional feature the metallic gauze is preferably oxidized so that the dark 30 back ground of the gauze makes the auxiliary spark readily visible through the aperture 18. From the above description it is believed the operation of the plug is obvious.

One advantage of our invention lies in 35 the fact that the auxiliary spark gap being located in the plug itself, separate devices usually used for the same purpose of intensifying the ignition spark becomes unnecessary and the attendant extra expense for 40 such intensifiers thereby eliminated.

Another evident advantage in our form of spark plug is the small number and simplicity of the parts used, which reduces the cost of manufacture and makes a less number 45 of parts liable to become deranged by vibration incident to travel.

The intensified ignition spark prevents accumulation of carbon on the electrodes with-

in the engine cylinder, and insures an explosion of gas at the proper time, and no gas 50 is thereby wasted, which is one form of economy of engine operation.

And lastly the wire gauze surrounding the auxiliary spark gap prevents the spark at this point from igniting any surrounding 55 gases or fumes that may be in the immediate vicinity of the engine and it will be readily understood this is an advantage in public garages or similar situations when the plug is used on automobile engines. 60

What we claim is:—

1. A spark plug having an outer housing and conductors forming an ignition and an auxiliary spark gap, a single piece insulating plug in said housing having a transverse aperture in its upper end accommodating the auxiliary spark gap, and a reduced diameter portion forming an annular shoulder, a metallic gauze cylinder on the plug surrounding the auxiliary spark gap, 70 an annular reinforcing strip attached to the bottom edge of the gauze cylinder and adapted to seat itself on the said plug shoulder, a cap provided with a projecting annular flange inclosing the upper end of the gauze 75 cylinder, and locking means for securing the cap on the end of the insulating plug aforesaid.

2. In a spark plug, a centrally disposed one piece insulating plug having a reduced 80 diameter portion forming a shoulder, a cylindrical metallic gauze thereon, a metallic reinforcing ring mounted on the lower edge of the said gauze and adapted to engage 85 against the shoulder of the insulating plug, a cap having an annular flange adapted to receive the upper edge of the cylindrical gauze, and means for securing the said cap on the end of the insulating plug.

In testimony whereof we affix our signatures in the presence of two witnesses.

LEO A. SCHAUER.
ERNEST C. MYERS.
